[57] CLAIM

The ornamental design for a tire tread, as shown and described.

DESCRIPTION

FIG. 1 is a front elevational view of a tire tread showing our new design, it being understood that the tread pattern is repeated throughout the circumference of the tire tread; FIG. 2 is a right side perspective view thereof; FIG. 3 is a left side perspective view thereof; FIG. 4 is a side elevational view of the right side thereof; FIG. 5 is a side elevational view of the left side thereof; and, FIG. 6 is an enlarged fragmentary front elevational view thereof.

The broken line showing of the tire sidewall in the drawings is for illustrative purposes only and forms no part of the claimed design.
